Original application May 21, 1938, Serial No.
209,170. Divided and this application January
9, 1939, Serial No. 249,933

9 Claims. (Cl. 179—171)

This invention relates to a radio receiver and more particularly to a tone control circuit for the receiver.

It is an object of applicant's invention to provide a continuously variable tone control and bass-boost by which the selectivity of the audio-amplifier may be varied from a normal frequency reproduction at one end of the tone control to bass-boost in center position and to high frequency cut-off at the other end of the range of tone control.

Tone control circuits with which applicant is familiar are relatively expensive and provide merely an adjustable means for cutting out or bypassing from the signal circuits different proportions of the high frequency currents and alternatively boosting different proportions of the lower frequency currents.

It is accordingly an object of applicant's invention to provide a continuously variable tone control by which the tone characteristics of the receiver may be varied from one end of the audio-frequency range to the other, said control circuit being inexpensive and relatively simple in character as compared with the prior art.

More specifically, it is an object of applicant's invention to provide a combination tone control of the variable type providing means for simultaneously boosting the bass notes and attenuating the high notes in varying proportions under the control of a single adjustable resistor unit.

Other and further objects and advantages of the invention will be apparent from the following description when taken in connection with the accompanying drawing showing a schematic diagram of a tone control circuit constructed in accordance with the invention.

The present application is a division of the application filed by William J. Schnell and Eugene W. Masters, as Serial No. 209,170, on May 21, 1938.

The single figure of the drawing illustrates a continuously variable tone control by which the tone characteristics of the receiver may be precisely adjusted as desired. As shown in this drawing, the thermionic tube 10, which may constitute the first stage of audio-amplification in the radio receiver, receives its audio-signal input through the input leads S₁ and S₂, the lead S₁ being preferably grounded. The lead S₂ is connected to the lead S₁ or to ground by a resistor or potentiometer 12 and a control grid 14 of the tube 10 is connected to the adjustable tap 16 of the resistor or potentiometer 12. The potentiometer 12 is tapped substantially at its midpoint by

a wire 18; a condenser 20 is connected between the wire 18 and the input lead S₂ and shunts the upper one-half of the potentiometer 12. The resistor or potentiometer 22, which is of the same order of magnitude as the potentiometer 12, is similarly provided with a midtap 24 grounded by the wire 26. One end of the potentiometer 22 is connected by a wire 28 and a series resistor 30 to the wire 18. A high frequency by-pass condenser 32 is connected between the wires 26 and 18 and shunts the left half of the potentiometer 22. The adjustable blade or wiper 33 of the potentiometer 22 is grounded as at 34. The other end of the potentiometer is connected by a wire 36, a high frequency by-pass condenser 38, and a wire 40 to the plate 42 of the tube 10.

The cathode 44 of the tube 10 is heated from the usual source (not shown) and is grounded as at 46, or otherwise connected to the other grounded points of the circuits shown. Plate 20 current is supplied to the tube 10 in the usual manner, as for example, through the choke 48 connected to the positive terminal 50 and to the plate 42. Output leads O¹ and O², in which a coupling condenser 52 is inserted, connect the output of the audio-amplifier 10 to the input of a second stage of audio-amplification or to the input of a power amplifier.

The operation of the circuit is substantially as follows. As the adjustable wiper 33 of the potentiometer 22 is moved to the right toward the midtap 24, the impedance of the parallel circuit, including the lower half of the potentiometer 12, the resistance 30 and the portion of the potentiometer 22 between the adjustable tap and the wire 28, increases. For the currents of the higher frequencies, the by-pass condenser 32 offers a path of much less impedance than the impedance of any substantial portion of the potentiometer between the tap 33 and the wire 28; hence as the tap 33 is moved to the right toward the center tap 24, the high frequency currents bypassed about the lower half of the potentiometer 12 and the potentiometer 22 will be substantially unaffected. The impedance of the condenser 32 to the signaling currents of lower or bass frequencies, is relatively high as compared to the impedance of the potentiometer 22 between the tap 33 and the wire 28. Consequently, as the wiper 33 is moved to the right toward the center tap 24, the voltage drop across the lower half of the potentiometer 12, due to the signal currents of relatively low or bass frequencies, will be increased.

When the wiper 33 is at the left-hand end of 55

the potentiometer 22, the condenser 32 is shunted out and the relatively small resistor 30 constitutes the total resistance in parallel to the lower half of the potentiometer 12. Consequently, the signal voltages impressed upon the tube 10 are substantially determined by the upper half of the potentiometer 12 and specifically that portion of the potentiometer which is between the adjustable tap 16 and the midtap of the potentiometer. 5 The condenser 20 permits a normal by-passing of the predominantly stronger, higher frequency currents. As the wiper 33 of the potentiometer 22 is moved to the right from the center tap 24 toward the wire 36, the impedance of the input circuit to the currents of different frequencies remains unchanged, since the center tap of the potentiometer is directly connected to ground. However, the impedance of the by-pass circuit connected to the output circuit of the tube 10 10 constantly decreases as the wiper 33 approaches the end of the potentiometer connected to the wire 36 and therefore more and more of the higher frequency currents are by-passed out of the output circuits. When the wiper 33 engages the 15 right-hand end of the potentiometer 22, the impedance of this high frequency by-pass circuit is a minimum and accordingly the condenser 38 acts to cut off the higher frequencies. The value of this condenser, however, is such as to offer 20 considerable impedance to the lower or base frequencies and hence said frequencies are properly transmitted by the output circuit to the succeeding stage of amplification.

The adjustable tap 16 of the potentiometer 25 12 may be employed if desired as a volume control, although it has to some slight extent a tone controlling effect. It will therefore be seen that the circuit illustrated in the drawing provides a continuously variable tone control where- 30 by high frequency cut-off is obtained simultaneously with the boosting of the lower or bass frequency, thereby giving a brilliant tone effect and that the circuit further provides a smooth control of tone from normal at one end to bass- 35 boost in the center and to high cut-off at the other end or limit of movement of the adjusting device.

In one actual installation made in accordance 40 with the invention, the circuit elements had the following values: Resistors 12 and 22 were each 45 a two-megohm, conventional volume control resistor; resistor 30 had a resistance of 75,000 ohms; the condenser 20 had a capacity of .00025 microfarad; the condenser 32 had a capacity of .003 50 microfarad; and the condenser 38 had a capacity of .005 microfarad.

Changes may be made in the form, construction and arrangement of the parts without departing from the spirit of the invention or sacrificing any of its attendant advantages, and the right is hereby reserved to make all such changes as fairly fall within the scope of the following claims.

The invention is hereby claimed as follows:

60 1. In a radio receiver, an audio amplifier having an input circuit, an output circuit, and tone control means in said input circuit, said control means comprising an input control impedance across which audio signal voltages are impressed, a second impedance in shunt to a portion of said 65 first impedance, a capacitance across a portion of said second impedance for by-passing the higher audio frequency currents from said second impedance, and means for varying the effective 70 value of said second impedance to vary the par-

allel impedance of the shunted portion of the control impedance and the second impedance whereby to vary the response of said amplifier to the currents of lower or bass audio frequencies while maintaining the response of the amplifier to currents of the higher audio frequencies substantially unaffected. 5

2. In a radio receiver comprising an audio amplifier having an input circuit, and tone control means in said input circuit, said means comprising an input control resistor across which audio signal voltages are impressed, a second resistor and a high audio frequency by-pass condenser connected in shunt to a portion of said second resistor, and a variable connection between said second resistor and one end of said input control resistor for continuously varying the value of the portion of said second resistor in shunt to the input resistor whereby to boost the bass audio frequencies as the variable connection increases the value of the portion of the second resistor in shunt to the first resistor. 10

3. In a radio receiver or the like, an audio amplifier having an input circuit and an output circuit, an impedance in said input circuit across which signal voltages are impressed, and a tone control circuit comprising a second impedance having a portion shunting a portion of said first impedance and a portion in said output circuit, a capacity shunting a portion of said second impedance and impedance adjusting means continuously adjustable along said second impedance for varying the value of the impedance in the capacity shunted portion thereof to adjustably control the boosting of the lower or bass audio frequencies while maintaining the higher audio frequencies substantially unaffected as the adjusting means is adjusted through a portion of its range of adjustment and for varying the value of the impedance not shunted by the capacity 35 40 45

to adjustably control the dissipation of the higher audio frequencies while maintaining the lower or bass audio frequencies substantially unaffected as the adjusting means is adjusted through another portion of its range of adjustment.

4. In a radio receiver or the like, an audio amplifier having an input circuit and an output circuit, an impedance in said input circuit across which signal voltages are impressed, and a tone 50 control circuit comprising an impedance network for boosting the signal voltages of the lower or bass audio frequencies and dissipating the higher audio frequencies, said impedance network having a portion of predetermined fixed value in said input circuit and another portion of predetermined fixed value in said output circuit, and continuously adjustable means for varying the value of the portion in said input circuit when adjusted through a portion of its range of adjustment and for varying the value of the portion in said output circuit when adjusted through another portion of its range of adjustment, whereby the response characteristic of the input circuit may be varied as said adjustable means is adjusted through a portion of its range of adjustment and the response characteristic of the output circuit may be varied as the adjustable means is adjusted through another portion of its range of adjustment. 55 60 65 70

5. In a radio receiver, an audio-amplifier comprising a thermionic tube having a cathode, a grid and a plate, an input control resistor, across which signal voltages are impressed, connected at one end to said cathode, a connection between 75

5 said resistor and said grid, tone control means connected between said control resistor, said cathode and plate, said tone control means comprising a potentiometer having the wiper there-
 10 of connected to said cathode and one end connected to an intermediate point on said input resistor, a high frequency by-pass condenser connected between said plate and the other end of said potentiometer and a high frequency by-pass condenser connected in shunt to a portion of said potentiometer and to said cathode.

15 6. In a radio receiver or the like, an audio amplifier having an input circuit and an output circuit, an impedance in said input circuit across which signal voltages are impressed, a tone control circuit comprising an impedance network of capacity and resistance for boosting the signal voltages of the lower or bass audio frequencies and dissipating the currents of the higher audio
 20 frequencies, said network having capacity and resistance portions of predetermined fixed value in said input circuit and another resistance portion of predetermined fixed value in said output circuit and continuously adjustable shunting means for varying the value of the resistance portion in said input circuit when adjusted through a portion of its range of adjustment and varying the value of the resistance portion in said output circuit when adjusted through another portion of its range of adjustment whereby the response characteristic of the input circuit to lower or bass audio frequencies may be varied while maintaining the currents of higher audio frequencies substantially unaffected as the adjustable means is adjusted through a portion of its range of adjustment and the response characteristic of the output circuit to the higher audio frequencies may be varied while maintaining the currents of lower or bass audio frequencies substantially unaffected as the adjustable means is adjusted through another portion of its range of adjustment.

25 7. In combination, a thermionic amplifier tube having grid plate and cathode electrodes, an input circuit having an impedance connected between said grid and cathode electrodes and across which impedance signal voltages are impressed, an output circuit connected between the plate and cathode electrodes, a second impedance connected to said first impedance and connected to one of said grid and cathode electrodes, a capacity connected across a portion of said second impedance for by-passing the higher audio frequencies from said second impedance, and
 30 an adjustable impedance shunting connection

35 from said second impedance to the connection of said second impedance to the said one of the grid and cathode electrodes for varying the response of said amplifier tube to the currents of lower or bass frequencies while maintaining the response 5 of the amplifier tube to currents of higher audio frequency substantially unaffected.

40 8. In combination, a thermionic amplifier tube having grid plate and cathode electrodes, an input circuit having an impedance connected between said grid and cathode electrodes and across which impedance signal voltages are impressed, an output circuit connected between the plate and cathode electrodes, a second impedance connected to said first impedance and connected to one of said grid and cathode electrodes, a capacity connected across a portion of said second impedance for by-passing the higher audio frequencies from said second impedance, a second capacity connected between said second impedance and said plate electrode, and a continuously adjustable impedance shunting connection from said second impedance to said first impedance and to said cathode electrode for varying the response characteristic of the input circuit to lower 25 or bass audio frequencies while maintaining the response of the input circuit to higher audio frequencies substantially unaffected as the adjustable impedance shunting connection is adjusted through one portion of its range of adjustment 30 and for varying the response characteristic of the output circuit to the higher audio frequencies while maintaining the response characteristic of the input circuit to lower or bass audio frequencies substantially unaffected as the adjustable 35 impedance shunting connection is adjusted through another portion of its range of adjustment.

45 9. In combination, an audio amplifier comprising a thermionic tube having a cathode, a grid and a plate, an input control impedance across which signal voltages are impressed, said input impedance being connected between said grid and cathode, tone control means connected between said control impedance, said cathode and said 45 plate, said tone control means comprising a voltage divider having the adjustable connection thereof connected to said cathode, one side of the voltage divider being connected to an intermediate point on said input impedance, a high 50 frequency by-pass condenser connected between said plate and the other side of said voltage divider and to said cathode.
